(57) **CLAIM**

The ornamental design for a wheel front face, as shown and described.

DESCRIPTION

FIG. 1 is a perspective view of a wheel front face showing a new design.

FIG. 2 is a front view thereof; and,

FIG. 3 is a side view thereof.

The broken lines in the drawings illustrate portions of the wheel front face in which the design is embodied that form no part of the claimed design.

1 Claim, 3 Drawing Sheets

FIG. 1

FIG. 2

FIG. 3
